TOWER STRUCTURE

Erastus R. St. John, Forest Hills, N. Y.

Application August 9, 1945, Serial No. 609,911

2 Claims. (Cl. 189—15)

(Granted under the act of March 3, 1883, as
amended April 30, 1928; 370 O. G. 757)

1

This invention relates to a tower structure and method of assembly and disassembly; particularly the invention relates to a radio antenna.

An object of this invention is to provide a tower structure such as a radio antenna that is capable of being assembled in a horizontal position close to the ground and then raised to a vertical position without the necessity of having men do any high climbing.

Another object is to provide a tower structure such as a radio antenna which can be dismantled into relatively short sections for convenient transportation.

Another object is to provide a simple and convenient method for erecting a tower.

Another object is to provide a tower structure such as a radio antenna that can be assembled and erected by relatively unskilled personnel.

Another object is to provide a tower structure such as a radio antenna that is suitable for tropical duty.

Further objects and advantages of this invention as well as its construction arrangement and operation, will be apparent from the following description and claims in connection with the accompanying drawings in which:

Fig. 1 is a front elevation of the radio antenna assembly in its erected position;

Fig. 2 is a plan view of the ground frame used with the assembly of Fig. 1.

Fig. 3 is an enlarged perspective view of a portion of the antenna assembly of Fig. 1;

Fig. 4 is a sectional view of one of the mast tops of the antenna assembly shown in Fig. 1;

Fig. 5 is a sectional view of the mast top taken on the line 5—5 in Fig. 4;

Fig. 6 is an enlarged view of one of the joints shown in Fig. 3;

Fig. 7 is a view of the base lock of the antenna assembly of Fig. 1; and

Figs. 8, 9, 10, 11 and 12 are schematic illustrations of progressive steps in the erection of the radio antenna assembly of Fig. 1.

Fig. 1 shows a tower generally designated as 11 comprising a vertical center member 12 integrally braced by cross struts 13 and tension rods 16. These members are shown in greater detail in Fig. 3. The tower 11 is rotatably supported as at 17 upon a trunnion 18 through approximately its lower midsection. The supporting trunnion 18 is engaged and supported by bearings 19 upon the tops of two masts 20 in turn rotatably secured to pedestals 21 upon a ground frame 22. This arrangement allows the tower 11 and masts 20 to swing or rotate in par-

2

allel vertical planes as will be described in detail below.

The base of the tower 11 is secured by a lock 23 connected to the ground frame 22. The masts 20 are provided with stays 24 which are also connected to the ground frame 22 and arranged such that in combination with the trunnion 18 and ground frame 22 they form a system of bracing for maintaining the masts 20 in a vertical position. These stays 24 can be comprised of sections of rod of convenient length shackled together as at 25 and provided with turnbuckles 26 so that they can be placed under a suitable tension. The ground frame 22 is provided with suitable earth anchorages 27 to resist upward forces caused by the wind and by the tackle used in erecting the tower.

Fig. 2 shows the arrangement of the ground frame 22. This is preferably buried below the surface of the ground. Suitable connections for the stays 24 are provided at the positions 28. The pedestals 21 are secured at 29 and the lock 23 for the tower base is secured at 30. The necessary connections for attaching snatch blocks and other sheaves and winches required for tilting the tower 11 and masts 20 from horizontal to vertical position (described below) are also connected to the ground frame 22.

Fig. 3 shows a typical portion of the tower 11. All members are made of an aluminum alloy or other light durable material of suitable strength. The center member 12 is made up of sections of tubular material of convenient length joined together as at 31. The tube sections can be of progressively decreasing diameter on each side of the supporting trunnion 18. The joints are tapered and keyed or otherwise secured and are machined for accurate fitting. Around the joints are collars 32 that can comprise half sections bolted together at 32a as shown in Fig. 6. These collars 32 are provided with connections as at 33 for the cross struts 13 and with lugs as at 34 having holes for receiving shackles 35 of the tension rods 16.

The cross struts 13 are also made of tubing. The end of each cross strut 13 is provided with suitable connections 36 having lugs provided with holes for receiving shackles 35 of the tension rods 16 (see Fig. 5). The vertical tension rods can be comprised of sections shackled together as at 37 so as to be of lengths of convenience in handling. The sizes of the cross struts 13 and tension rods 16 can also progressively decrease on each side of the trunnion 18. Optionally other tower designs may be used

with the trunnion and mast arrangement without departing from the principles of the invention as described and claimed herein.

The trunnion 18 and bearing 19 on one of the mast tops are shown in detail in Figs. 4 and 5. The bearing 19 consists of a split block having a base section 38 residing on a top plate 39 of the mast 20. A cap section 40 fits over the trunnion 18 and is secured to the base section 38 by bolts 41 (Fig. 4) which also hold the base section 38 to the top plate 39 of the mast. The trunnion 18 is provided with a spool 42 within which it rotates. Between the spool 42 and the split block is rubber insulation 43 that both insulates the tower 11 from the ground and allows slight movements without binding any of the connections between the tower 11 and the mast 20. The trunnion 18 extends through one of the tubular cross struts 13, through the spool 42 in the split block bearing 19, and is secured by means of a threaded extension 44 provided with a washer 45 and nut 46.

Figs 4 and 5 also show the manner in which the stays 24 are secured to the mast top. Lugs 47 having holes 48 for receiving the shackles 25 of the stays 24 are bolted or otherwise secured to the mast top below the bearing 19. Fig. 5 further shows connecting members 36 for receiving the shackles 35 of the tension rods 16.

Fig. 7 shows the ground lock 23 in detail. This lock 23 comprises a two piece cast block 49 bolted or otherwise secured to the ground frame 22 as at 50. The tower base is provided with a rubber insulated gudgeon pin 51 that fits in the block 49 and in the base of the center member 12.

Fig. 7 also shows a base collar 52 having lugs 52a for receiving the tension rods 16. This base collar 52 is further provided with a bail 53 for connecting tackle as at 54 for erecting the tower 11.

In assembling and erecting the antenna the ground is first suitably graded, trenches and holes for the ground frame 22 and anchorage 27 excavated, the ground frame 22 and anchorages 27 are assembled in place and the trenches and anchorages filled and thoroughly tamped. The pedestals 21 for the masts 20, the ground lock 23 and connections for stays 24 and for sheaves, snatch blocks and winches are then connected to the ground frame 22. The two masts 20 are assembled in a horizontal position together with the trunnion 18 of the tower 11 and are attached to the pedestals 21. The stays 24 are attached to the mast tops. By gin poles, mobile cranes or other convenient means the mast ends are raised to substantially the position shown in Fig. 8 and supported by any suitable means as at 55.

The tower 11 is next assembled from its component sections starting from the trunnion 18 and working toward both ends. Tower 11 is supported at intervals by suitable means as at 56 (Fig. 9) to enable the bracing and struts to clear the ground. When the tower 11 is completely assembled with all rods and joints tightened (as in Fig. 9) a dolly 57 is placed under the top end. The bails 53 are attached to the tower base and tackle lines 58 and 59 are secured thereto. All supports are now removed and the tower 11 rests on the dolly 57 and trunnion 18.

The tower base and mast tops are next pulled upward and in the direction of the tower base by mobile cranes, gin poles or other convenient means to a reasonable height such as that shown in Fig. 10. At this position the dolly 57 is pulled forward by means of a winch 60 and tackle 61 until the masts 20 are in a vertical position as

shown in Fig. 11. Stays 24 are then connected to the ground frame and properly tightened.

The tower 11 is now raised by swinging it through a vertical plane about the axis of the trunnion 18 by means of tackle lines 58 and 59 and winches 62 and 63 as shown in Fig. 11. The base of the tower 11 swings into a half section of the ground lock 23 and is secured by bolting the other half section in place.

Fig. 12 shows the tower 11 in the final position with all stays properly tightened and braced.

If the tower is to be erected by experienced erectors, automatic torque wrenches can be used to control the initial tension in all the rods and stays. If, however, the tower is to be assembled and erected by unskilled personnel, all parts are actually fabricated and machined, all threading of rods, devices, turnbuckles, sleeve nuts and all taper keyed joints between pipe sections are made so accurately that, when every screwed joint is tightened up until shouldered, contact surfaces are in contact. By this means predetermined initial stresses are produced by unskilled workers.

By thus applying the proper initial stresses the deflections are reduced as much as 50 per cent in some antenna designs and dangerous whipping eliminated.

All parts of the proposed radio antenna can be boxed in crates of, for example, 20 feet in length. All pieces are properly marked for convenient assembling when shipped out.

By the use of the antenna and method of erecting as disclosed herein towers of a height of, for example, up to 300 feet and above can be shipped to remote spots and assembled and erected by relatively unskilled personnel. This tower is particularly well adapted for erection and use in the tropics where ice and sleet are not encountered.

It is to be understood that various changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A portable tower structure assembled from a plurality of relatively small individual units and adapted to be erected and taken down by personnel confined to the ground, said tower structure comprising a ground frame embedded in the ground, said frame having a plurality of anchors exposed at the surface of the ground, a pair of elongated and rigid supports disposed in parallel spaced relation, said supports each having one end swingably attached to an anchor so that said supports can swing in parallel paths, a transverse trunnion rigidly interconnecting the ends of said supports, stays between said anchors and the ends of said supports adjacent said trunnion for securing said supports in vertical position with said trunnion extending horizontally, an elongated and integrally braced, single tube tower formed from a plurality of individual sections, said tower being rotatably mounted upon said trunnion and adapted to be disposed in vertical position with one end depending from the trunnion into proximity with the ground, and a lock on said ground frame for engaging said depending tower end to lock the tower in vertical position.
2. A tower structure comprising a ground frame embedded in the ground, said frame having a

plurality of anchors exposed at the surface of the ground, a pair of elongated and rigid supports disposed in parallel spaced relation, said supports each having one end swingably attached to an anchor so that said supports can swing in parallel paths, a transverse trunnion rigidly interconnecting the ends of said supports, stays between said anchors and the ends of said supports adjacent said trunnion for securing said supports in vertical position with said trunnion extending horizontally, a tower rotatably mounted upon said trunnion and adapted to be disposed in vertical position with one end depending from the trunnion into proximity with the ground, and a lock on said ground frame for engaging 15 said depending tower end to lock the tower in vertical position.
